FILTER PANEL

Oliver H. Schaa, Shaker Heights, Ohio, assignor
to Air-Maze Corporation, Cleveland, Ohio, a
corporation of Delaware

Application July 11, 1947, Serial No. 760,320

5 Claims. (Cl. 183—69)

1

This invention relates to improvements in a filter panel for filtering particles out of a gaseous stream.

One of the objects of the present invention is to provide a filter panel formed of strips of screen mesh material which may be cheaply manufactured in continuous lengths and cut and assembled in a filter frame as disclosed hereinafter.

Another object of the present invention is to provide a filter panel of the type described having passageways extending uninterruptedly from front to rear of the panel for the free passage of air in case the panel becomes clogged with dirt but the passageways being so constructed and arranged that normally the air stream or gas stream cannot pass directly through the same.

Another object of the present invention is to provide a filter panel each layer of which is provided with a zig-zag crimp, of Z form, which provides one advantage in that the strip of screen mesh material will pass through a crimping roller without tendency to move out of a straight line and with the second advantage that the crimps placed relatively close to the front and rear edges of a given layer of material aid in the holding of the filaments of the screen mesh along the edges so as to prevent ravelling.

Still another object of the present invention is to provide a filter panel comprising a plurality of layers of screen mesh material provided with corrugations in Z form, with the meshes of adjacent layers reversed, so that a plurality of filaments near each edge of the filter panel are in close juxtaposition so as to hold a liquid adhesive material such as oil between the filaments.

Other objects and advantages of my invention will be apparent from the accompanying drawings and description and the essential features of the same will be set forth in the appended claims.

In the drawings,

Fig. 1 is a front elevational view of a filter panel embodying my invention with a portion of the front protective screen broken away to more clearly show the construction;

Fig. 2 is a transverse sectional view greatly enlarged taken along the line 2—2 of Fig. 1;

Fig. 3 is a diagrammatic view illustrating some of the details involved in the layout of an individual layer of filter material; while

Fig. 4 is an end view of the same taken approximately from the position 4—4 of Fig. 3 and enlarged and exaggerated to illustrate the point.

One form of my invention is shown in Figs. 1 and 2 and comprises a main frame 10 which is of channel form having webs 10a parallel to the di-

2

rection of stream flow and having edge flanges 10b overlying the edges of the filter element around the entire periphery of the panel as clearly shown in a fragmentary view in Fig. 2. It will be noted that the front and rear faces of the panel are opened for air flow in the direction of the arrows of Fig. 2. I prefer to form my filter element of screen mesh material of the order of sixteen meshes per inch similar to ordinary fly screen although it will be understood that other types of stiff mesh material might be used to carry out my invention. I prefer to form my filter elements by cutting the screen mesh material into elongated strips under two inches in width in one form of my invention although of course this dimension may be varied according to the thickness of the filter panel to be formed. These elongated strips of screen material are passed between corrugated crimping rolls to provide corrugations of Z form as shown in Figs. 2 and 3.

In one form of my invention the dimension A measured at right angles to the corrugations is three-eighths of an inch between adjacent ridges. This makes the dimension B at right angles to the general direction of stream flow approximately seven-sixteenths of an inch. In one form of my invention, the dimension J of Fig. 4 is approximately three-sixteenths of an inch and the form of corrugation is approximately as shown there. Referring now to Fig. 3 in one preferred form of my invention the dimensions C is three-eighths of an inch and the dimension D is one inch. At the same time, the angle E is at an angle of approximately thirty degrees to the general direction of stream flow through the panel. 30 Referring now to Fig. 3 in one preferred form of my invention the dimensions C is three-eighths of an inch and the dimension D is one inch. At the same time, the angle E is at an angle of approximately thirty degrees to the general direction of stream flow through the panel. 35 At the point of first change in direction of the crimp or corrugation the angle F is approximately one-hundred and twenty degrees. At the next reversal of crimp direction the angle G is approximately one-hundred and twenty degrees and the angle H is again approximately thirty degrees from the direction of air flow through the panel. While variations may be made from the dimensions and angles just mentioned, it is desirable that they be so chosen that there is no 40 possibility of the direct passage of particles through the filter panel along a line between adjacent crimps such as the line K which is a dotted line in Fig. 3. It should be noted here that the full zig-zag lines represent 45 the theoretical direction of the ridges of the corrugations whereas actually the true crests of the ridges are of curved form, as clearly shown in Fig. 4, and prevent a direct path through a single corrugation along any line similar to K.

50 After the strips of screen mesh material are

corrugated as above described, they are then cut to proper length to fit within the frame 10. As illustrated in Fig. 2, if the corrugations of the layer 11 are bent in one direction then the corrugations of the next layer 12 are reversed and the corrugations of the next layer 13 again extend in the same direction as those of the layer 11. I may either form the layers 11 and 13 in one machine and the layers 12 in another machine or strips formed as in the layer 11 may be reversed in position to form the layer such as 12. It will be noted that the layers as placed in the filter panel permit air flow from front to rear of the panel generally parallel to the direction of the extension of corrugations. In other words, the stream flow is generally parallel to the screen rather than through the screen. When the filter panel has been filled with the screen layers, preferably but not necessarily, a front and rear protecting screen 14 and 15 is provided which may be of coarse hardware cloth, expanded metal, or other suitable protective and strong material.

Preferably, adjacent layers are so arranged that adjacent corrugations cross each other as shown in the mid portion of Fig. 2. Here the uppermost ridges of each layer nearest the observer are shown in the heavier lines. These ridges for the layer 13 are shown in broken lines beneath the layer 12. It will be noted that the short portions 12a of the corrugations of the layer 12 which form troughs (shown in lighter line) are in crossing relation with the portions 13a of the ridges of the layer 11 directly beneath. Because each ridge and trough has a somewhat flattened form as shown in Fig. 4 a number of wire filaments are thus brought into direct contact or into sufficiently close contact so that when the filter panel is coated with adhesive material, such as the oil commonly used, little reservoirs of this oil are formed between the filaments which touch or almost touch at the front and rear faces of the panel. This greatly aids the dust holding capacity of the filter.

One of the difficulties which has occurred in the construction of filter panels of assembled screen layers having zig-zag corrugations therein, has been a tendency of the strips of screen material to travel to one side when passing through the crimping rolls. In the present design this has been overcome because in passing through the crimping rolls the portions 16 and 17a (Fig. 3) provide equal tendencies to pull the strip toward the right and left and therefore counterbalance each other. Likewise, the portions 17b and 18 have a similar effect. The net result of the entire construction is that the elongated strips pass through the corrugating rolls without any tendency to move toward the right or left.

Another disadvantage of previous filter elements constructed similar to mine, has been a tendency of the edge filaments to ravel at the front and rear faces of the filter panel. The arrangement of my Z form corrugations overcomes this difficulty which I have endeavored to illustrate in Fig. 4. The wires 18a extending crosswise of the strip of screen mesh material coming downwardly across the portion 18 of the corrugation have a tendency to continue downwardly as shown in Fig. 4. The wires 18b on the opposite side of the corrugation, due to the angle G, have a tendency to extend upwardly as shown

in Fig. 4. It results from this construction that the edge filament 20 extending longitudinally of the strip is held in position and does not ravel easily.

5 The operation of my improved filter panel should now be apparent. When an air or other gaseous stream flows through the panel in the direction of the arrows of Fig. 2, particles collect on the adhesive coated wires as the stream works 10 itself from the front to the rear face of the panel through the maze of wires. There is practically no tendency for the gaseous stream to flow directly in the Z shape passageways between adjacent corrugations, at least until the walls of the 15 corrugations have become so coated with particles as to force this type of flow. Obviously, when this occurs it is time to clean the panel. It will be noted from Fig. 2 that the corrugations of the layer 12 are in direct contact with the 20 corrugations of the layers 11 but in crossing relationship. This creates a turbulence as the stream passes through the panel and increases its efficiency. It should be apparent to those skilled in this art that my panel has very low resistance 25 to the passage of a gaseous stream and has a very high dirt holding capacity.

While the above description has been devoted to the collection of solid particles, it should be understood that my improved filter panel may 30 also be used to remove liquid particles from a gaseous stream.

Filters of this general type are known to me having no bend or one bend between the front and rear face of the panel. It is possible for 35 stream-borne particles to pass straight through the "no bend" device or through a single layer of screen and then straight through the "one bend" device. In my two-bend arrangement or Z form of corrugation, a particle starting down 40 one corrugation and continuing in a straight line must pass through several layers of screen before finding a passageway leading to the opposite face of the panel.

What I claim is:

45 1. A filter panel for placement in a fluid stream and comprising a plurality of generally parallel contiguous foraminous mesh screens extending in the general direction of stream flow, each of said screens being provided with parallel corrugations generally Z form in plan, the corrugations of one screen crossing the corrugations of adjacent screens in crossed relation, and frame means for causing a fluid stream so to flow.

55 2. A filter panel for placement in a fluid stream and comprising a plurality of generally parallel contiguous foraminous mesh screens extending in the general direction of stream flow, each of said screens being provided with parallel corrugations generally Z form in plan, the corrugations of one screen crossing the corrugations of adjacent screens in crossed relation, the middle leg of the Z form being longer than each of the end legs of said Z form, and frame means for causing a fluid stream so to flow.

3. A filter panel for placement in a fluid stream and comprising a plurality of generally parallel contiguous foraminous mesh screens extending in the general direction of stream flow, 70 each of said screens being provided with parallel corrugations generally Z form in plan, the corrugations of one screen crossing the corrugations of adjacent screens in crossed relation, the middle leg of said Z form being of the order of twice as long as each of the end legs of said

Z form, and frame means for causing a fluid stream so to flow.

4. A filter panel for placement in a fluid stream and comprising a plurality of generally parallel contiguous foraminous mesh screens extending in the general direction of stream flow, each of said screens being provided with parallel corrugations generally **Z** form in plan, the corrugations of one screen crossing the corrugations of adjacent screens in crossed relation, the middle leg of said **Z** form being of the order of twice as long as each of the end legs of said **Z** form, the angle between the middle leg of said **Z** form and each of the end legs thereof being of the order of one hundred and twenty degrees, and frame means for causing a fluid stream so to flow.

5. The combination of claim 1 wherein the

angle between the legs of said **Z** form and the extent of said legs is such as to block a clear straight passage through a single corrugation of one screen from one side of said panel to the other.
